UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,393,430.

Specification of Letters Patent.

Patented Oct. 11, 1921.

Application filed January 4, 1918. Serial No. 210,267.

To all whom it may concern:

Be it known that I, HENRY P. CLAUSEN, a citizen of the United States, residing at Mount Vernon, in the county of Westchester and State of New York, have invented certain new and useful Improvements in Telephone Systems, of which the following is a full, clear, concise, and exact description.

This invention relates to telephone exchange systems and more particularly to such systems wherein both automatic and manual lines are used.

In such systems where a part of the lines are equipped with calling dials for setting up a connection automatically to any of the lines, and other lines are equipped with the well-known manual instruments and arranged to have connections established therefrom by means of multiple jacks at a manually operated switchboard, it is desirable to maintain secrecy between automatically connected parties. It is therefore necessary in order to accomplish this end to have an arrangement at the manual switchboard for preventing the operator from listening in through the multiple jack of either of the parties to an automatically established connection.

The object of this invention is to provide such an improved arrangement of circuits and apparatus at an operator's position whereby her supervision over automatically established connections is removed.

The principal feature of this invention lies in the means for temporarily disconnecting the line multiples of both parties to an automatically established connection from the manual switchboard.

In the drawings, which show a preferred embodiment of the invention, a line switch is shown to connect an automatic line to an idle trunk circuit. It is understood, however, that any other well-known means may be employed for establishing such connection.

In the drawings sub 1, sub 2 and sub 4 are telephones equipped for automatic service and sub 3 and sub 5 are telephones arranged for manual service. Switchboard multiple jacks 7 and 8 are associated with each automatic line as for example sub 1. An operator's cord 6 is diagrammatically shown by means of which she may establish a connection from a manual line to any other line. Switchboard multiple jacks 10 and 11

are associated with each manual telephone line, as for example sub 5.

Assume now that the subscriber at sub 1 desires a connection with the subscriber at sub 4. By removing his receiver from the switchhook, relay 14 is energized due to a circuit being closed from ground, back contact and inner left-hand armature of magnet 13, conductor 29, middle armature and back contact of relay 15, conductor 22, sub 1, conductor 23, outer armature and back contact of relay 15, middle left-hand armature and back contact of magnet 13, through the winding of relay 14 to battery. The operation of relay 14 closes a circuit from ground, through the left-hand winding of magnet 13 to battery. The energization of magnet 13 operates all of its armatures and plunger 12. The operation of the left-hand outer armature and front contact places a busy test condition on the sleeve of line multiple jacks 7 and 8, from battery through resistance 28 and conductor 21. The operation of the middle and inner left-hand armatures of magnet 13 opens the energizing circuit of relay 14 above traced. The operation of the plunger 12 closes, at its two upper sets of contacts, the line conductors 22 and 23 to the idle trunk conductors 24 and 25 respectively. The trunk 24, 25 ends in a selector or connector switch, and the closure of the line through to the switch brings about a circuit change in a well-known manner which places a ground on conductor 26, and ground through a resistance on brush 38. A circuit is then established from ground on conductor 26, through the lower contacts operated by plunger 12, over conductor 27, through the right-hand winding of magnet 13 to battery for holding magnet 13 operated.

A circuit is also closed from ground on conductor 27 through the inner back contact of relay 15 to test terminal 30 to cause the calling line sub 1 to test busy. Relay 14 is slow to release and will therefore not open the circuit through the left-hand winding of magnet 13 before the right-hand winding has been energized. The connection is then completed in the well-known manner by the use of the dial in sub 1 and the switch at 36, 37, 38 to sub 4. At the end of the conversation, the receiver at sub 1 is replaced to the switchhook, thereby opening the line and causing a change in the selector or connector 36, 37, 38, causing it to release and remove the

ground from conductor 26, thereby releasing magnet 13, withdrawing plunger 12 and freeing the line.

Assume now that the automatic subscriber at sub 2 calls another automatic subscriber at sub 1. His line is extended to the connector brushes 33, 34, 35 in a well-known manner. When the brushes are set on the terminals 32, 31, 30 of the line sub 1 a circuit is closed from ground supplied by the connector circuit, brush 35, terminal 30, inner armature and back contact of relay 15 through the right-hand winding of magnet 13 to battery. The right hand winding of magnet 13 is so designed as to operate the left-hand armatures, but not to operate the plunger 12. The operation of magnet 13 cuts off the line relay 14 and places a busy test condition on the multiple jacks 7 and 8 as described above.

Assume now that the automatic subscriber at sub 1 calls the manuel line at sub 5. His call is extended to the connector brushes 36, 37, 38 which are stepped onto the terminals 39, 40, 41 respectively of the line sub 5. A circuit is then closed from ground through a resistance in the connector circuit to brush 38, terminal 41, the inner armature and back contact of relay 16, conductor 46, through the winding of relay 17 to battery. The operation of relay 17 closes a circuit from battery through the winding or relay 17, through the left-hand armature and front contact of relay 17, to the test terminals of multiple jacks 10 and 11, causing the line to test busy at the operator's switchboard. From this point the call is completed and connections restored to normal in a well-known manner.

In the three cases assumed above, we have traced calls originated at an automatic station and noted that during the establishment of such connections and during conversation magnet 13 is operated. If at such times an operator should attempt to call or to listen in on a line sub 1 by plugging in over the busy test condition on jack 7 or 8, it is obvious that no talking or listening connection will be afforded, since neither relay 15 of an automatic line, or relay 16 of a manual line can be operated.

Assume that the manual subscriber at sub 3 desires a connection with the automatic line at sub 1. The connection is extended to the operator's cord circuit 6 in a manner to be described later. The operator then tests the multiple jack 7 or 8 of the line in the usual manner, and finding it free, she inserts the plug 9 of her calling cord 6. When the plug 9 is inserted in jack 7 or 8 a circuit is closed from battery through the lamp 50, resistance 51, sleeve of plug 9, sleeve of jack 7 or 8, conductor 21, outer left-hand armature and back contact of magnet 13, through the winding of relay 15 to

ground. The operation of relay 15 closes at its inner armature and front contact, a circuit from ground to terminal 30, to hold the line of sub 1 busy, and at its middle and outer armatures and front contacts, it 70 closes the talking connection from ground, the repeating coil winding 52, the tip of plug 9 and jack 7 or 8, conductor 20, outer armature and front contact of relay 15, conductor 23, sub 1, conductor 22, middle armature and front contact of relay 15, conductor 19, the ring of plug 9, and jack 7 or 8, through the winding of supervisory relay 54 and repeating coil winding 53 to battery. 75

Assume now that the manual subscriber at sub 3 calls the manual subscriber at sub 5. The call is extended to the operator's cord in a manner to be described later, she tests the line sub 5 by touching the tip of her plug 9 to the sleeve of jack 10 or 11, and 80 finding the line idle inserts the plug 9 in the jack 10 or 11. A circuit is then closed from battery through lamp 50, resistance 51, sleeve of plug 9 and jack 10 or 11, the left-hand armature and back contact of relay 17, conductor 47 through the winding of relay 16 to ground. The operation of relay 16 closes at its inner armature and front contact, a circuit from ground to test terminal 41, to supply a busy test condition 85 for the line to automatic switches, and at its middle and outer armatures and front contacts it closes the talking circuit from ground repeating coil 52, through the tip contact of plug 9 and jack 10 or 11, conductor 49, outer armature and front contact of relay 16, conductor 43, sub 5, conductor 42, middle armature and front contact of relay 16, conductor 48, the ring contacts of plug 9 and jack 10 or 11, through supervisory 90 relay 54 and repeating coil winding 53 to battery. 100

In the two cases last assumed, we have traced calls originated at the manual line sub 3 and completed manually to automatic line sub 1 and manual line sub 5 respectively. If during the time when such connections are established an operator should plug into a multiple jack as 7 or 8 in the first case, and 10 or 11 in the second case, over 110 the busy test condition, by the use of another cord circuit, in a well-known manner, it is obvious that such act would supply an additional multiple listening and talking connection to the lines sub 1 and sub 5 respectively. 115

The details of the circuit of a calling manual line are shown in the drawings in connection with sub 5. When the calling manual line sub 5 is closed by the removal 120 of the receiver, a circuit is closed from battery, left-hand winding of relay 18, through the inner right-hand armature and back contact of relay 17, conductor 45, middle armature and back contact of relay 16, conduc- 125

tor 42, sub 5, conductor 43, outer armature and back contact of relay 16, conductor 44, right-hand outer armature and back contact of relay 17, through the right-hand 5 winding of relay 18 to ground. The operation of relay 18 closes a circuit from ground on its front contact, through its armature and answering lamp 55 to battery. Upon receiving the signal from lamp 55 the operator inserts her plug thereby operating relay 16 in a well-known manner, which relay in turn breaks at its middle and outer armatures and back contacts, the operating 10 circuit of relay 18, which in turn extinguishes lamp 55.

From the above description it is obvious that all connections completed manually, are accessible at all times to the switchboard operator, and that all calls originated at an 15 automatic subscriber's station are inaccessible to such operator at all times regardless of the character of the called party's line.

What is claimed is:

1. In a telephone system, a central office, 25 a telephone line terminating in said office, a plurality of automatic switches having access to said line, an operator's switchboard at said office, a plurality of multiply connected jacks at said switchboard normally 30 disconnected from said line, a plurality of manually operable link circuits at said switchboard, and means including a relay effective when one of said switches is not connected to said line to connect any one of 35 said link circuits through any one of said jacks to said line.

2. In a telephone system, a central office, a line bank in said office, a plurality of lines terminating in said line bank, a plurality of 40 switches having access to said lines at said line bank, a plurality of multiply connected jacks associated with each of said lines at said office and normally disconnected from said lines, a relay individual to each of said 45 lines to connect said line to said multiply connected jacks, and means for rendering said relay ineffective when said line is engaged by one of said automatic switches.

3. In a telephone system, a manual switch- 50 board, a contact bank for automatic switches,

a line terminating in said contact bank, a jack at said manual switchboard associated with said line, and a relay individual to said line under control of an operator at said manual switchboard effective to extend said 55 line to said jack at said manual switchboard.

4. A telephone exchange system comprising a telephone line extending to a central office, a plurality of multiple terminals thereat, a plurality of multiply connected jacks 60 thereat normally disconnected from said line, automatic switches arranged to engage said terminals, a relay associated with said line for controlling the connection of said line to said jacks, means individual to said line 65 for rendering said relay ineffective when said terminals are engaged by one of said switches, a manually operable link circuit, and means for rendering said relay effective to connect said line to said jacks when said 70 link circuit is connected to one of said jacks.

5. In a telephone system, a central exchange, a plurality of manual and automatic telephone lines extending to said exchange, a plurality of automatic link circuits for extending certain of said lines, a plurality of manually operable link circuits for extending other lines, means including a relay for connecting any one of 75 said manually operable link circuits to any 80 one of said lines and a second relay operable to connect said certain lines to said automatic link circuits and to render the first named relay ineffective.

6. In a telephone system, telephone lines, 85 means for interconnecting said lines, means including a multiple jack and a relay through contacts of which relay operator's supervision is supplied to connections between 90 said lines where the call originated at certain lines, and means including another relay made operative to extend another line and to prevent operator's supervision to a connection where the call originated at said other line.

In witness whereof, I hereunto subscribe my name this 28th day of December, A. D. 95 1917.

HENRY P. CLAUSEN.
